UNITED STATES PATENT OFFICE

2,438,711

SHOE WITH DETACHABLE UPPER

Raymond A. Leach and Geraldine M. Leach,
Los Angeles, Calif.

Application March 2, 1945, Serial No. 580,522

1 Claim. (Cl. 36—2.5)

1

This invention relates to shoes particularly to that type used by women, but also for men's shoes.

The main object is to provide a shoe of construction and design so that varied uppers can be provided on a common foundation to suit the tastes and colors of the wearer.

Another object is to provide a shoe with a foundation portion of standard construction such as the high heel, oxford, slipper, wedge sole, or all other types with means for quick assembly therewith of an upper portion which is provided in various colors and materials.

A further object of the invention is to provide a shoe with a foundation portion provided for attaching the upper portion through loop and string, clips and hooks or other means.

A further object is to provide women's shoes of a type whereby a foundation portion can be bought with one or more upper portions in color and design to suit the tastes of the wearer and to provide means for the lady to make a change of color in her shoes to match the colors of her other wearing apparel when so desired without purchasing several pairs of shoes.

Other objects and advantages will appear as the description progresses and in which reference to the accompanying drawings may be had and in which:

Fig. 1 is a side elevation of one embodiment of our invention.

Fig. 2 is a plan view of an upper portion of the shoe shown in full developed position.

Fig. 3 is a side elevation of the foundation.

In the drawings like parts are designated by like numerals. 10 is a sole portion having built thereon the loops or clips 11 and the toe box 12 and the counter 13. The shoe upper portion 14 is provided with loops or clips 15 coacting with the corresponding loops 11 of the foundation as best shown in Fig. 1. The assembly cord 16 is threaded through the loops 11 and loops 15 causing the upper portion 14 to be assembled in fixed position to the foundation 10. The upper portion 14 is provided with lacing eyelets 17—17 through which the cord 16 is threaded to hold the units of the shoe in complete assembly. By thus using a single lacing cord as a draw string which extends both through the interengaging series of loops 11 and 15 and the cooperating rows of eyelets 17 a quickly operable satisfactory take-up

2

fastening means is provided which compensates for wear and may be utilized to keep the shoe snugly fitted to the foot at all times.

It is to be understood that others versed in the art may make modifications and changes but such changes and modifications are to be embodiments of this invention within the scope of the appended claim.

What we claim is:

- 10 A shoe comprising a sole and heel tread-forming portion, a toe box fixed on the forepart of said tread-forming portion, a heel counter fixed upon the rear part of the tread-forming portion, a flexible upper adapted to be received about said toe box and heel counter and to enclose the foot of the wearer therein, the end portions of said upper having their transverse edges disposed to assume spaced apart parallel positions at the rear of the heel counter and having rows of openings adjacent said transverse edges, coacting loops formed on the bottom longitudinal edge of said cover and the upper perimeter of the tread-forming portion, and a lacing element adapted to be laced through said coacting loops and the 20 respective rows of openings in the end of said upper to detachably connect the cover with the tread-forming portion and adjustably connect the ends of the upper for maintaining the upper in smoothly drawn condition upon the toe box, 25 the heel counter, and the foot of the wearer.
